UNITED STATES PATENT OFFICE.

FRANKLIN H. SMITH, OF PESHTIGO, WISCONSIN.

GATE

Application filed December 10, 1926. Serial No. 154,011.

This invention relates to gates.

Objects of this invention are to provide a gate or a door which is so constructed that it may be moved laterally from the roadway in a novel manner by means accessible to a driver or other person from either side of the gate, and at points spaced from the gate so that a driver, for example, may pull upon a cable and open the gate without dismounting from the vehicle, and after passing the gate, may pull upon a second cable and close the gate.

Further objects are to provide a simple mechanism which is effective in operation for lifting the gate and swinging it into the desired position with a minimum of friction, and to provide a construction which is eminently practical and may be cheaply produced.

This invention is designed primarily for gates but it is to be understood that it is equally applicable to doors or other barriers of this general type.

An embodiment of the invention is shown in the accompanying drawings in which:—

Figure 1 is a side elevation of the gate and the associated mechanism showing in full lines the gate in closed position, and in dotted lines the successive positions occupied by the gate when it is opened;

Figure 2 is a view at right angles to Figure 1 with parts in section.

Referring to the drawings, it will be seen that the gate is indicated by the reference character 1, and is of rectangular construction. The transverse slats or bars have been omitted from the drawings for the sake of clearness, but it is to be understood that the gate may be of any usual form. When the gate is in closed position, its front end contacts with a stop 2, which is carried by the outer gate post 3. Preferably, this stop is provided with a plurality of rollers 4 to minimize friction. On the other side of the roadway, a pair of uprights or gate posts 5 are provided which extend upwardly a material distance above the gate. These uprights carry a set of pulleys 6 which have axes extending at right angles to the plane of the gate and carry pulleys 7 which have their axes extending parallel to the plane of the gate. A pair of cables 8 extend over these pulleys and downwardly, and are provided with terminal members 9 which are herein-after described with greater detail. The other ends of the cables extend over pulleys

10 carried by posts 11 spaced a material distance from the gate and adjacent the roadway and terminate in balls or other members, as indicated at 12.

The gate is provided centrally with a guide 13 (see Figure 1) which has an elongated slot 14. This slot is provided with notches 15 at its ends. A pair of pins 16 extend through the slot 14 and are carried by members 17 on opposite sides of the gate. These pins furnish bearings for the upper ends of a pair of parallel links 18 on opposite sides of the gate. The lower ends of these links are pivoted to a stationary member 19 (see Figure 1). If desired, a single pair of links could be substituted for this double pair without departing from the spirit of this invention.

At the rear of the gate, trunnions 20 project from opposite sides and fit within slots 21 formed in the upper end of the links 22. The lower ends of these links are pivoted to a bearing member 23 carried by a suitable stationary post.

The lower ends of the cables 8 have their terminal members 9 attached to the cross head or member 17 by means of short links 24, so that the tension of the cable can be transmitted to the gate in a manner hereinafter to appear.

A second bumper 25 is provided, similar to the bumper 2, and is equipped with rollers 26 in order to minimize friction.

In operating this gate, it is merely necessary to pull downwardly upon one of the cables 8 at its free end. This elevates the gate and causes it to swing laterally into the position indicated by the dash line, until it strikes the bumper 25. At this time, the gate is arrested in its lateral motion and settles downwardly, the slot 21 in the lever 22 permitting the lowering of the rear end of the gate, and the slot 14 in the member or slide 13 permitting the levers 18 to swing towards the rear end of the gate, thus lowering the gate so that the levers occupy the dotted line position shown in Figure 1.

When it is desired to close the gate, it is merely necessary to pull downwardly on the other cable. This elevates the gate and swings it into contact with the bumper 2 and it then settles downwardly into the full line position shown in Figure 1.

Thus, it will be seen that the gate can be operated from either side to either open it or close it. It will be seen further that the

gate freely swings upwardly and rearwardly when it is being opened, and that the levers and pins cooperate to permit the gate to settle downwardly at either extreme of 5 its motion.

It is to be noted that both of the pins 16 pass through the slot 14, as previously described, and consequently maintain the gate horizontal in all positions. Further, it is to 10 be noted that the lever 22 is not parallel to either of the levers 18. Consequently, as the gate rocks to the dotted line position, the pin 20 will ride up in the slot 21 of the lever 22. Thereafter, the gate will settle 15 down after it strikes the bumper. The levers 22 act as guides for the rear end of the gate and prevent its moving out of position.

It will be seen further that the construction is very simple, and is eminently practical, and may be easily produced.

Although the invention has been described in considerable detail, such description is intended as illustrative rather than limiting as the invention may be variously embodied 25 and as the scope of such invention is to be determined as claimed.

I claim:

1. The combination of a gate, a pair of uprights mounted on opposite sides of the 30 rear end of the gate, levers pivoted adjacent the lower ends of said uprights and having a pin joining their upper ends, a horizontally slotted guide receiving the pin of said levers and carried by said gates intermediate its ends, a second pair of levers pivoted adjacent their lower ends at a point spaced from the lower ends of said first mentioned levers and having slotted upper ends, pins 35 carried by said gate adjacent its rear end and fitting within the slotted upper ends of said last mentioned levers, and cables extending downwardly and operatively coupled to the upper ends of said first mentioned levers.
- 40 2. The combination of a gate, a pair of uprights mounted on opposite sides of the

rear end of the gate, levers pivoted adjacent the lower ends of said uprights and having a pin joining their upper ends, a horizontally slotted guide receiving the pin of said 50 levers and carried by said gates intermediate its ends, a second pair of levers pivoted adjacent their lower ends at a point spaced from the lower ends of said first mentioned levers and having slotted upper ends, pins 55 carried by said gate adjacent its rear end and fitting within the slotted upper ends of said last mentioned levers, and cables extending downwardly and operatively coupled to the upper ends of said first mentioned levers, and spaced bumpers adapted to engage opposite ends of said gate when 60 said gate is swung to opposite extreme positions.

3. The combination of a pair of uprights, 65 a gate positioned between said uprights and having a guide mounted intermediate the ends of said gate and provided with an elongated slot having notches at its ends, a pair of levers pivoted adjacent the lower 70 ends of said uprights and having a pin passing through said slot, a second pair of levers pivoted at their lower ends at points spaced from the lower ends of said first mentioned levers and having slotted upper ends, pins 75 carried by said gate and sliding in the slots of said last mentioned levers, cables extending downwardly from said uprights and operatively joined to the upper ends of said first mentioned levers, means for guiding 80 said cables in opposite directions, and a pair of bumpers arranged in spaced relation and adapted to engage opposite ends of said gate when said gate is moved into either extreme position, said slots permitting said gate to 85 settle downwardly after said gate has been arrested in its motion by said bumpers.

In testimony that I claim the foregoing I have hereunto set my hand at Peshtigo, in the county of Marinette and State of Wisconsin.

FRANKLIN H. SMITH.
